BRUSH STRIP CONSTRUCTION

Brooks E. Nelson, Chagrin Falls, Ohio, assignor to The Osborn Manufacturing Company, Cleveland, Ohio, a corporation of Ohio

Application August 26, 1954, Serial No. 452,319

12 Claims. (Cl. 15—182)

This invention relates as indicated to brush strip construction, and more particularly to improved brush strip produced in a manner to avoid difficulties encountered in the past.

Brush strip comprising an elongated metal channel-form back within which brush bristle material is secured by means of an elongated retaining element such as a wire has become an important article of commerce and is produced in large quantities. While much brush strip is employed in the manufacture of hand brushes and dusters, a principal use is in the manufacture of power driven rotary brushes. Such brushes may be composed of a series of annular sections formed by individual turns of brush strip with the brush material extending generally radially outwardly therefrom or a long length of brush strip may be wound upon a mandrel to circularize the same and produce a cylindrical or "roller" brush. Brushes of this type are becoming of increasing importance in industry.

Preferred forms of brush strip are shown and described in Peterson Patent 2,303,386 and in my prior Patent 2,609,242. Various other forms of brush strip are also known in the art characterized by an elongated back within which the brush material is secured by a wire retaining element extending longitudinally therein. Brush strip of the type indicated is produced in continuous lengths on automatic machines and is then wound on an appropriate mandrel or arbor as produced to circularize the same. Lengths of such circularized brush strip comprising one or more turns are thereupon severed from the resultant helix to produce the desired brush element. When severed in the form of straight lengths, a small amount of brush material may be shed at the severed ends but when wire retaining teeth of the type disclosed in Patent 2,303,386 are provided, such shedding will be minimized. The severed ends of the brush strip back may also be pinched to close the channel.

When the brush strip is circularized, it will immediately be apparent that the wire retaining element is required to describe a circle of greater diameter than the inner periphery of the brush back although when the brush strip is straight, the length of the wire and back will obviously be the same. Accordingly, the wire is greatly tensioned by the circularization operation, tending further to compact the brush material retained beneath it. Then when the circularized brush strip is severed, the tension on the wire is released and it contracts abruptly to substantially its original length, permitting shedding of the brush material adjacent the two ends of the circularized strip. Slippage of the wire longitudinally of the circularized brush strip is also objectionable for the reason that it drags against and tends to dislocate some of the brush material.

In order to alleviate this situation, the wire may be made of relatively soft metal (i. e. having low yield point) so that it will stretch permanently during circularization sufficiently to conform to the elongated path it now takes. The wire, however, cannot be too soft if the brush is to be driven at high speeds since it must have sufficient ten-

2

sile strength to secure the brush bristle material against the effect of centrifugal force. Also, such relatively soft wire will work-harden when it is stretched and therefore still tend to contract when the brush strip is severed.

5 Extreme tensioning of the retaining wire during circularization has yet another undesirable effect in that, by further compacting the brush material, it shifts radially inwardly of the brush element away from the securing teeth which overlie it. When the brush strip is thereafter severed, the wire may then be relatively loose between the compacted brush bristle material in the bottom of the channel back and the overlying teeth, permitting excessive shedding of the brush material.

It is accordingly a principal object of my invention to 15 provide novel brush strip having an elongated retaining element securing the brush material within the brush back which will accommodate itself to the longitudinal stresses imposed when such brush strip is circularized.

Still another object is to provide such brush strip which 20 will not tend to shed brush material unduly when such strip is circularized and then severed to provide annular brush elements of one or more turns.

Other objects of the invention will appear as the description proceeds.

25 To the accomplishment of the foregoing and related ends, said invention then comprises the features herein-after fully described and particularly pointed out in the claims, the following description and the annexed drawing setting forth in detail certain illustrative embodiments of 30 the invention, these being indicative, however, of but a few of the various ways in which the principle of the invention may be employed.

In said annexed drawing:

Fig. 1 is a semi-diagrammatic view illustrating the 35 manufacture and circularization of my new brush strip; Fig. 2 is a transverse section taken on the line 2—2 on Fig. 1; and

Fig. 3 is an enlarged view of the elongated brush material retaining element incorporated in such brush strip.

40 The preferred example of brush strip embodying the principles of my invention illustrated in the drawing may be produced in a manner generally similar to that employed in the manufacture of the brush strip disclosed and claimed in Peterson Patent 2,303,386. Teeth 1 are 45 punched up adjacent the edges of a flat elongated sheet metal strip 2, ordinarily steel, with such teeth lying in planes transverse of such strip and somewhat spaced from the respective strip edges as shown. Brush bristle material 3 is placed transversely of the strip and an elongated wire retaining element 4 is laid thereon along the longitudinal center line of the strip. The strip is then deformed into a channelform back 5 with the teeth 1 extending inwardly from the channel sides and closely overlying retaining wire 4 as best shown in Fig. 2. The 50 brush bristle material 3 is thereby doubled about wire 4 and held in place within the channel back by the latter.

When such brush strip is circularized as shown in Fig. 1, for example, it is readily apparent that wire 4 is caused to define a circle of considerably larger radius 60 than the inner periphery of the brush back. The radially outer edges of the channel backs are stretched by such circularization, and wire 4 must likewise stretch sufficiently to accommodate the difference between the circumference of the circle it describes and the circumference described by the inner periphery of the brush back.

65 I have found that if the retaining element 4 is made of somewhat ductile material such as low carbon steel SAE 1020 annealed wire, and such wire is also crimped 70 in the manner illustrated in Fig. 3 of the drawing, it will stretch permanently sufficiently to avoid consequential contraction upon severing of the circularized brush strip

and accordingly the objectionable results previously encountered are avoided. It is important that such crimp should be uniform longitudinally of the wire and also that the wire should be uniformly soft so that the stretching which occurs will likewise be substantially uniform along the length of the wire. The crimp will preferably be approximately in the form of a sine wave defining a smooth curve. Thus, I have found that when the retaining wire 4 has a diameter of .072 inch, for example, a full curve of the crimp may have a .27 inch frequency and an over-all amplitude of from .100 to .175 inch. The smaller the inner diameter of the circularized brush element, the greater should be the amplitude of the crimp. In the past, the greatest difficulty has been encountered when brush strip has been circularized about a relatively small radius.

The channel back 5 may be formed of a variety of materials as well known in the art, including aluminum, copper, brass, steel, stainless steel, and even certain synthetic plastic materials. Likewise, a wide variety of brush material may be utilized including tampico fiber, horsehair, wire, cord, plastic coated wire, plastic coated cord, synthetic plastic monofilaments, and various types of fabric buff materials. The retaining element 4 may be of any suitable ductile material capable of taking the desired crimp including low carbon annealed steel, aluminum, copper, and brass.

It will be seen from the foregoing that I have provided novel brush strip capable of being circularized about a relatively small radius to form annular rotary brush elements when severed into desired lengths, such brush strip continuing firmly to retain the brush material therein despite the effects of such circularizing and severing operations. The circularizing operation effects a stretching and straightening out of at least a portion of the crimp in the wire retaining element, and such latter element is of sufficient softness or ductility that when the brush strip is thereafter severed, there is little tendency to revert to the previously crimped condition. In other words, the stretching of the retaining element is permanent without, however, causing any very substantial cold working of the element, undue compacting of the brush material thereunder, or the build-up of longitudinal stresses resulting in shrinkage of the wire when severed.

The crimped wire retaining element of my invention should preferably be of round cross-section to avoid undue local concentrations of stress in the bristles secured thereby. The flexible channel back will ordinarily be substantially straight-sided and the wire will, of course, be crimped before being secured therein. Since the crimp will not usually be entirely reduced by the tension resulting from circularization or like deformation of the brush element, it is of further service in engaging the inwardly projecting teeth to prevent shifting in use.

Other modes of applying the principle of the invention may be employed, change being made as regards the details described, provided the features stated in any of the following claims or the equivalent of such be employed.

I therefore particularly point out and distinctly claim as my invention:

1. Brush strip having an elongated sheet metal channel-form back, a wire retaining element extending separately longitudinally within such channel, a continuous layer of brush material retained beneath said wire and protruding from said back, and teeth punched in from the respective channel sides overlying and engaging said wire to hold the latter in place; said wire being smoothly continuously crimped relative to the channel sides throughout its length and sufficiently ductile substantially to maintain its stretched condition when elongated and such crimp is at least partially straightened by imposition of longitudinal tension thereon, and the sides of said channel back being substantially flat.

2. Brush strip having an elongated channel back, a

separate wire retaining element extending longitudinally within such channel, and a continuous layer of brush material retained beneath said wire and protruding from said back; said wire being smoothly continuously crimped relative to the channel sides throughout its length and therefore of greater absolute length along its sinuous course than said back and sufficiently ductile substantially to maintain its stretched condition when elongated and such crimp is at least partially straightened by imposition of longitudinal tension thereon.

3. A brush element including a support portion having an elongated channel, a separate elongated retaining element extending longitudinally within such channel, and a continuous layer of brush material retained beneath said element and protruding from said channel; said element being crimped relative to the sides of such channel and therefore of greater absolute length along its sinuous course than said back as well as sufficiently ductile substantially to maintain its stretched condition relative to said back when such crimp is at least partially straightened by imposition of longitudinal tension thereon.

4. A brush element including an elongated straight flexible back having a longitudinal channel therein, an elongated retaining element extending separately longitudinally within such channel, and a layer of brush material retained beneath said element and protruding from said channel; said element being pre-crimped relative to said straight channel back and therefore of greater absolute length along its sinuous course than said back to facilitate stretching relative to said back when said back is flexed.

5. Brush strip having an elongated sheet metal channel-form back, a single wire retaining element extending separately longitudinally within such channel, a layer of brush material retained beneath said wire and protruding from said back, and teeth punched in from the respective channel sides overlying and engaging said wire to hold the latter in place; said wire being of annealed low carbon SAE 1020 steel and smoothly pre-crimped relative to the sides of said channel back in substantially a sine wave curve having a frequency of approximately .27 inch and an over-all amplitude of approximately .100 to .175 inch in the case of .072 inch diameter wire, said wire being of greater absolute length along its sinuous course than said back and sufficiently ductile substantially to maintain its stretched condition when such crimp is at least partially straightened by imposition of longitudinal tension thereon due to circularization of said brush strip, the remaining crimp in said wire engaging such teeth and tending to prevent longitudinal shifting of said wire.

6. In a brush element having a unitary circularized sheet metal channel back, and brush material retained in said back and protruding radially outwardly therefrom; a smoothly crimped wire retaining member extending separately longitudinally within such channel and overlying said brush material effective to secure said brush material in place, such crimp being relative to the sides of said back assisting in preventing shifting of said brush material and in accommodating longitudinal stresses in said wire.

7. In a brush element having a circularized substantially straight-sided sheet metal channel back, and folded brush material retained in said back and protruding radially outwardly therefrom; a single smoothly crimped round wire retaining member extending separately longitudinally within such channel overlying the fold of said brush material and effective to secure said brush material in place, such crimp being relative to the sides of said channel back assisting in preventing shifting of said brush material and in accommodating longitudinal stresses in said wire.

8. A brush element in accordance with claim 7 also having teeth punched in from a channel side of said back to overlie and secure said wire, said teeth addi-

tionally engaging such crimp to assist in restricting shifting of said wire.

9. In the method of forming a circularized brush strip element having radially outwardly extending brush material including the step of securing brush material in an elongated flexible sheet metal channel back beneath a single wire retaining element; the preliminary step of smoothly and uniformly crimping said wire relative to such back, and the subsequent step of tensioning said wire during circularization of said strip at least partially permanently to reduce such crimp and thereby effectively elongate said wire.

10. In the method of forming a circularized brush strip element having radially outwardly extending brush material including the step of securing brush material in an elongated flexible sheet metal channel back beneath a single wire retaining element; the preliminary step of crimping said wire prior to insertion in such channel, and the subsequent step of tensioning said wire during circularization of said strip at least partially permanently to reduce such crimp and thereby effectively elongate said wire relative to the inner periphery of such circularized back.

11. In the method of forming a brush element including the step of securing brush material in an elongated flexible sheet metal channel back beneath a wire retaining element; the preliminary step of crimping said wire, and the subsequent step of deforming said back longitudinally to tension said wire at least partially permanently to reduce such crimp and thereby effectively elongate said wire.

12. In a brush element having a sheet metal channel back, teeth protruding inwardly from the channel sides, and folded brush material retained in said back with both end portions protruding therefrom; a separate wire brush material retaining member disposed longitudinally within said channel beneath said teeth and overlying said folded brush material to secure the latter therein, said wire having an undulating conformation relative to the sides of said back adapted to engage said teeth to resist longitudinal displacement relative to said back, and also being of greater absolute length along its sinuous course than said back as well as sufficiently ductile to permit permanent stretching both of such undulations and of the wire itself when said back is subsequently circularized with said brush material extending radially outwardly, thereby forcing said wire to take a longer path than the inner periphery of said back, but said wire having a high ultimate strength safely to secure said brush material in place in said circularized back.
